UNITED STATES PATENT OFFICE.

MICHAEL SIERSDORFER, OF LOUISVILLE, KENTUCKY.

COMBINED INKSTAND, PISTOL-CASE, AND BURGLAR-ALARM.

SPECIFICATION forming part of Letters Patent No. 425,347, dated April 8, 1890.

Application filed April 25, 1889. Renewed March 11, 1890. Serial No. 343,549. (No model.)

To all whom it may concern.

Be it known that I, MICHAEL SIERSDORFER, a citizen of the United States, residing at Louisville, county of Jefferson, State of Kentucky, have invented a new and useful Combined Inkstand, Pistol - Case, and Burglar-Alarm, of which the following is a specification.

My invention relates to a case or holder by which a pistol is placed within convenient and instant reach of a cashier or other person in charge of money or other valuables, the said case being made to do duty as the base of an inkstand, concealing its purpose of pistol-case.

Referring to the accompanying drawings, which form a part of this specification, Figure 1 is a perspective view of a combined pistol-case and inkstand embodying my invention, the door being thrown partly open. Fig. 2 is a vertical section to illustrate the alarm details.

1 is a box or case, which may simply rest on the counter or table or may be screwed fast thereto. This box serves as the base of an inkstand, and this appears to a stranger to be its sole purpose. Secured to the top of case 1 is a call-bell 2, having a spring-knob 3 for ordinary hand use. This bell, however, is so arranged in connection with clock-work 4 as to be rung automatically by the wide opening of door 5, as shown in Fig. 1. The said door 5 has a spring-hinge 6, which, on depression of spring-catch 7, operates to swing the door wide open, as indicated in said Fig. 1. On closure of the door it becomes automatically locked by action of the catch 7.

A shelf 8, that projects interiorly from the door 5, supports a pistol 9, which is securely held in place by means of spring-clips 10.

The pivoted latch 7 is held by spring or gravity to the normal position shown in Fig. 1, and a hook 7' with a sloping nose is so located on the door as on closure thereof to momentarily lift the inner part of the said latch, which then, by dropping behind the shoulder of the said hook, automatically locks the said door by the mere act of closing the same. It will thus be seen that the door automatically locks by the simple operation of closing it, and is automatically and instantaneously swung wide open by the mere act of springing the latch.

Any suitable alarm clock-work may be employed to sound the bell 2. For example, 11 is

a cog-wheel, which, when the attached main-spring 12 is wound up, has a tendency to rotate in the opposite direction and to operate through a pallet 13 and a clapper 14 to strike the bell with rapidly-repeated blows. Such action, however, is rendered impossible in the door's closed condition by the engagement of rod or detent 15, that projects from the door with lug or projection 16 of said cog-wheel.

The only way of sounding the bell when the door 5 is closed is to give a single call by depression of the knob 3. In this act the knob 3', which forms the inner terminus of the spring-piston 3'', presses upon and moves the pallet and through it the clapper. The device is thus available as an ordinary office call-bell, and as this use of it does not sound the alarm nor open the door its presence is not suggestive of a burglar-alarm.

Having thus described my invention, the following is what I claim as new therein and desire to secure by Letters Patent:

1. The combined inkstand and pistol-case, substantially as set forth—that is to say, said stand having a hollow or box-formed base 1, a door 5, having latch 7 and hook 7', whereby said door is automatically locked by the act of closing, and a spring 6, whereby said door is automatically swung wide open on release of said latch, said door having an internal shelf 8 and clips 10 to hold a pistol in convenient position for instant use.

2. The combination of an inkstand having box-formed base, whose door carries a concealed pistol-rack and has a latch 7, whereby it is automatically locked by the act of closing, and a spring 6, whereby it is automatically swung wide open on release of said latch, said door 14 being in the described combination with cog-wheel 11, having lug 16, mainspring 12, pallet 13, and clapper 14, the same being also combined with the spring-piston 3'', with knobs 3 3' of a combined call and alarm bell 2, as and for the purposes set forth.

3. The combination of inkstand, the box-formed base, the self-opening door thereof, the pistol-rack projecting from the inner side of and concealed by said door, and the alarm and call bell, substantially as set forth.

MICHAEL SIERSDORFER.
